UNITED STATES PATENT OFFICE.

ROBERT E. FRAME, OF ST. LOUIS, MISSOURI, ASSIGNOR TO AMERICAN CAR & FOUNDRY COMPANY, OF ST. LOUIS, MISSOURI, A CORPORATION OF NEW JERSEY.

TANDEM-SPRING DRAFT-RIGGING.

1,026,741.

Specification of Letters Patent Patented May 21, 1912.

Application filed January 19, 1909. Serial No. 473,079.

To all whom it may concern:

Be it known that I, ROBERT E. FRAME, residing at St. Louis, Missouri, and being a citizen of the United States, have invented 5 certain new and useful Improvements in Tandem-Spring Draft-Rigging, of which the following is a full, clear, and exact description, such as will enable others skilled in the art to which it appertains to make and 10 to use the same, reference being had to the accompanying drawings, which illustrate the preferred form of the invention, though it is to be understood that the invention is not limited to the exact details of construction 15 shown and described, as it is obvious that various modifications thereof will occur to persons skilled in the art.

In said drawings: Figure 1 is a side elevational view of the improved draft rigging, 20 being partly in section. Fig. 2 is a plan view showing the intermediate follower stops, partly in section. Fig. 3 is a transverse sectional view taken just forwardly of the intermediate follower stop. Fig. 4 is a fragmentary detail view showing the manner of connecting the intermediate follower stop to the draft sills. Fig. 5 is a front elevational view.

The object of the invention is to provide a 30 new and improved draft-rigging wherein the draft sills are firmly connected by means forming a part of the draft-rigging, to prevent lateral bulging of the said draft sills, as well as for other reasons hereinafter referred to.

Referring to the parts A—A are draft sills which are shown of channel shape, but which may be of any form best adapted for service as required.

40 B—B are front and back draft lugs secured to the draft sills by riveting, or in any suitable manner.

C is the drawbar.

D is the drawbar yoke.

45 E—E are the tandem springs held between front and back followers F F, and G is the vertical thimble employed and placed between the rear follower of the forward spring and the forward follower of the rear spring.

50 H—H are the follower thimbles commonly employed to hold the springs in proper position, a filler I being provided between the rear end of the drawbar yoke and the next adjacent follower F.

Between the draft lugs B—B is an intermediate follower stop member 1, which is provided with forwardly and rearwardly extending flanges 2 by means of which said intermediate follower stop member 1 is securely connected with the draft sills A, said member bridging the gap between said draft sills, as best shown in Fig. 3, wherein the bridge portion 3 extends over the movable parts of the draft-rigging and is cut out sufficiently to permit passage thereunder of the drawbar yoke and the elongated rivets which extend through said yoke and the thimble G.

The member 1 is provided with follower seats 4—4, on which bear respectively the rear follower of the forward spring and the forward follower of the rear spring. Between the seats 4—4 member 1 is provided with the vertical legs 5, which extend from the top of the draft sills to a plane somewhat below the lower flanges of said sills, as best shown in Figs. 1 and 3. The intermediate follower stop member 1, may be separately formed and can be readily applied to any standard tandem spring draft rigging, leaving all parts of the draft rigging open and easily accessible, so that repairs, or the substitution of new parts for damaged parts can be conveniently made. It should be noted, in this connection, that the forming of the stop member 1 independently of the stops B permits the use of the stops 1 of the same size in connection with draft gears of different capacities, as by placing the stops B at a suitable distance from the stop 1 to accommodate springs of different lengths. The bridge portion 3 serves to bind the leg portions 5 inseparably together so as to present the shoulders 4 on the opposite legs, at all times, in proper alinement to receive the center followers F; this in addition to the important function of binding the draft sills together when in operative position, as set forth. These results are obtained in a single, simple and inexpensive casting such as may be manufactured and sold independently of the precise capacity and details of the draft gear with which it is to be employed. Connecting the draft lugs B—B on each side of the draft rigging and connected also with the bottom flanges 6 of the intermediate member 1 are straps 7 which serve as supporting beams for the

followers. When the parts are in their normal position the vertical thimble G is in alinement with the vertical legs 5 of the member 1, but when the draft gear is subject to buffing or pulling strains the position of the vertical thimble is somewhat rearwardly or forwardly of said vertical legs. Thus in buffing the follower F bearing against the front side of the intermediate member 1 will be stopped by the vertical legs 5 of said intermediate member, while the rear-most follower will be held against the draft lugs farthest from the drawbar, while in pulling the position of the parts will be reversed; that is, the forward follower of the rear spring will abut against said vertical legs and the forward follower of the forward spring will abut against the draft lugs nearest the end sill M. Owing to the connection of the intermediate follower stop member 1 with the draft sills, spreading of said draft sills during buffing or pulling stresses will be prevented.

To permit of sufficient metal in the bridge portion 3, it is preferred that the draft lugs B shall extend below the plane of the draft sills A, as clearly shown in Fig. 1, said draft lugs being wider at the flanged ends which are impinged by the followers F than at their opposite ends, which

are contracted, as shown, so as to come within the area of said draft sills.

Extending forwardly and rearwardly of the intermediate follower seats 4 the member 1 is provided with ribs 9 which extend inwardly sufficiently far to serve as guides to hold the shorter intermediate followers F in correct alinement during operation of the draft gear, as in buffing and pulling. It will be noted in Fig. 2 that the end followers F are of sufficient length to extend almost across the gap between the draft sills while the intermediate followers are somewhat shorter to permit seating thereof on the seats 4 of the casting 1. 45

Having described the invention, what I claim is:

In a tandem spring draft rigging, front and back draft lugs secured to the draft sills, an independent intermediate combined bridge and follower stop spanning the middle portion only of the yoke and abutting the intermediate followers. 50

In witness whereof I have hereunto set my hand in the presence of two witnesses. 55

ROBERT E. FRAME.
